(57) **CLAIM**

We claim the ornamental design for a pruner, as shown and described.

DESCRIPTION

FIG. 1 is a front elevation view of the claimed design; FIG. 2 is a rear elevation view of the claimed design of FIG. 1;

FIG. 3 is a front, left perspective view of the claimed design of FIG. 1;

FIG. 4 is a rear, right perspective view of the claimed design of FIG. 1;

FIG. 5 is a rear, left perspective view of the claimed design of FIG. 1; and,

FIG. 6 is a front, right perspective view of the claimed design of FIG. 1.

The ornamental design which is claimed is shown in solid lines in the drawings. The broken lines represent portions of the pruner and form no part of the claimed design.

1 Claim, 6 Drawing Sheets
